UNITED STATES PATENT OFFICE

135,739

DESIGN FOR A SLICING MACHINE

Egmont H. Arens, New York, N. Y., and Theodore C. Brookhart, Troy, Ohio, assignors to The Hobart Manufacturing Company, Troy, Ohio, a corporation of Ohio

Application August 22, 1942, Serial No. 108,002

Term of patent 14 years

To all whom it may concern:

Be it known that we, Egmont H. Arens and Theodore C. Brookhart, citizens of the United States of America, residing at New York, in the county and State of New York, and Troy, county of Miami, and State of Ohio, respectively, have invented a new, original, and ornamental Design for a Slicing Machine, of which the following is a specification, reference being had to the accompanying drawings, forming a part thereof in which,

Fig. 1 is a side elevational view of a slicing machine showing our new design;

Fig. 2 is a side elevational view from the opposite side thereof;

Fig. 3 is a perspective view thereof from the operator's end of the machine; and

Fig. 4 is a perspective view on a reduced scale from the opposite end of the machine.

The design comprises a base forming a plane cover portion in front of the knife and a plane slice receiving tray rearwardly thereof, an arcuate shaped knife guard, a gage plate the upper edge of which is defined by a generally parabolic curved surface, and a portion located rearwardly of the knife and extending upwardly from said slice tray merging smoothly with said base adjacent the outer edge thereof with a tapering rounded upper surface, all substantially as shown.

We claim:

The ornamental design for a slicing machine substantially as shown and described.

EGMONT H. ARENS.
THEODORE C. BROOKHART.
